JOHN W. BAKER, OF PARKERSBURG, WEST VIRGINIA,

Letters Patent No. 69,156, dated September 24, 1867.

IMPROVEMENT IN FIRE-PLUGS.

The Schedule referred to in these Letters Patent and making part of the same.

TO ALL WHOM IT MAY CONCERN:

Be it known that I, JOHN W. BAKER, of Parkersburg, in the county of Wood, and State of West Virginia have invented certain new and useful Improvement in Fire-Plugs, of which the following is a full, clear, and exact description, reference being had to the accompanying drawing, which makes part of this specification.

It is well known that great losses frequently result from the fact that in severe weather the fire-plugs are frozen up, so that it is necessary to melt the ice in them or thaw them out with hot water before they can be used. It is the object of my invention to preclude the possibility of such an occurrence, and the disastrous and troublesome delays attendant upon such freezing of the plugs, by shutting off the water at the main, and draining the service or supply pipe, so that it shall be emptied and continue empty whenever the fire-plug is not in actual use, and the improvements claimed herein consist in the means of accomplishing this object, as hereinafter described. In the drawings—

Figure 1 is a vertical longitudinal section through the fire-plug and the supply pipe, and

Figures 2, 3, and 4 are sections of the water-cock.

The service pipe B is tapped into the main in the usual manner, and so that it may slightly incline upwards from the main to the elbow-joint, for the purpose of facilitating the draining of this pipe, as will be presently described. The upright portion of the pipe B may be adjusted in the box in any suitable manner. As near to the main as practicable I fit into the supply pipe B a two-way cock, A, which is turned to the position shown in fig. 4 when it is desired to let on the water, which is forced from the main through the cock into the pipe B. When the water is shut off from the main, the cock is turned to the position shown in figs. 1 and 2, in which position the waste-ways i I will permit the water in the service pipe to drain off through the cock into the sewer or into the ground. These waste-ways i I, it will be seen, are closed when the water is turned on from the main.

To work the cock A, I mount a bevel-wheel, C, upon the end of its plug, and gear into this wheel a corresponding wheel, D, mounted upon one end of a shaft, E, which is supported in suitable bearings, and which carries on its opposite end a bevel-wheel, F, which gears into a corresponding wheel, G, supported upon the lower part of a vertical rod or shaft, G', provided at its lower end with a stop or any suitable bearing, and at its upper end by the cap of the box or case of the plug through which it passes. Upon this upper end of the shaft G' is mounted a hand-wheel, by turning which in one direction the gearing will open the cock, and by turning it in the opposite direction the cock will be closed. It is obvious that if desirable, for security against tampering or meddling with the plug, this upper end of the shaft G' might be supported in the upper part of the box or casing without projecting through it, and be worked through the cap or top by a spanner fitting over the end of the shaft.

The service pipe and the gearing and its bearings should be enclosed in a box or casing, of such strength and material as may be requisite to protect the mechanism from becoming clogged or being strained, and to admit of ready access to the parts when repairs are necessary. The bottom of this casing should be perforated to admit of the escape of waste water.

By means of the device above described the water is shut off immediately at the main, and the pipe between the main and the mouth of the plug perfectly drained, so that there cannot be any possible obstruction in the plug from the formation of ice; and it is obvious that nothing short of the absolute freezing of the main will prevent the ready flow of water to the plug when the cock is turned on.

I have deemed it best to provide for working the cock by gearing, because from the comparatively long periods during which fire-plugs remain unused the accumulation of rust or other accretions might render a different mechanism less certainly effective, or less sufficient for all emergencies, in the fire-plug; but in a separate patent issued to me, of even date with this, I have described my invention as applied to hydrants.

What I claim herein as new, and desire to secure by Letters Patent, is—

The combination, substantially as described, of a shut-off valve or stop-cock and waste-way immediately at the main, with a train of gearing operated from the plug.

In testimony whereof I have hereunto subscribed my name.

JOHN W. BAKER.
